UNITED STATES PATENT OFFICE.

JULIUS S. SAMUELSON, OF DULUTH, MINNESOTA.

LIQUID-VENDING MACHINE.

1,373,914.

Specification of Letters Patent.

Patented Apr. 5, 1921.

Application filed January 26, 1920. Serial No. 353,938.

To all whom it may concern:

Be it known that I, JULIUS S. SAMUELSON, a citizen of the United States, residing at Duluth, in the county of St. Louis and State of Minnesota, have invented certain new and useful Improvements in Liquid-Vending Machines, of which the following is a specification, reference being had therein to the accompanying drawing.

10 This invention relates to liquid vending devices and has special reference to such a device for dispensing various forms of beverage and one that is operated automatically by a coin.

15 The principal object is to provide a simple and practical device of this character.

Other objects and advantages of the peculiar construction will appear in the further description of the invention.

20 In the accompanying drawings forming part of this application:

Figure 1 is a vertical sectional view through one unit of the device showing portions thereof in perspective.

25 Fig. 2 is a plan view of the rotating disk which controls the operation of the drinking cup table.

Fig. 3 is a plan view partly broken away of the completely assembled machine, except 30 that the beverage supply bottles are removed.

Fig. 4 is a front elevation of a portion of the mechanism above the upper deck, and

35 Fig. 5 is a fragmental side elevation of the coin conduit and its co-operative parts.

In the drawings I have illustrated what might be termed a double decked support, the lower deck or platform being illustrated at 1 and the upper deck at 2, they being 40 spaced apart by any suitable form of stanchion or uprights desired and it is to be understood that the entire mechanism may be housed within a suitable case not shown and forming no part of the present invention.

45 Spaced slightly above the lower platform and mounted thereupon in any desired manner is a circular table or cup-support 3 it being loosely carried upon the upright shaft 4, the upper end of which is journaled with 50 in the platform or deck 2. In the table 3 are formed preferably 6 circular cup-receiving holes they being equally spaced circumferentially adjacent the outer edge of the table and designed to progressively reg- 55 ister with the discharge of the cup-container

illustrated at 6 mounted upon the upper face of the deck 2.

This cup-container is of the common well known type which holds a plurality of stacked paper cups and readily discharges 60 by gravity a single cup at the reciprocation of the handle 7. An inclined upwardly extending guide 8 is fixed adjacent the forward end of each hole to assist the cup in entering same and a depending shield 9 extends 65 from the bottom of the cup-container for a like purpose and may be of any form desired. There is a fixed upstanding post 10 adjacent each cup-receiving hole in the table for controlling the movement of the latter 70 and about the shaft adjacent the table is a spiral spring 11, one end being rigidly fixed to the shaft as at 12 and the other end fixed to the table as at 13, thus when the shaft is turned by a mechanism hereinafter 75 described, contractive stress will be applied to the spring which will tend to rotate the table unless the latter is held against such tendency, and the rotating of the shaft 4 is intermittent and in step with other parts of 80 the mechanism, to be described later.

Above the deck 2 is mounted in any desired manner a rectangular shaped cooling receptacle 14 in which is contained a coil of tubing 15 and a rectangularly shaped measuring cup 16 for each one of the liquid supply jars or bottles 17 which are supported in an inverted position on the platform or table 18 above the receptacle 14. These coils and measuring cups are spaced from each other 85 within the receptacle 14 to permit of cracked ice surrounding same for cooling purposes. Each bottle 17 is connected with its respective coil preferably by a suitable piece of rubber tubing 19 and the lower end of each coil 15 communicates with its respective measuring cup 16 through a horizontally disposed cylindrical chamber 20 said chamber or cylinder having a port 21 centrally thereof and communicating with the interior of the measuring cup. In the top of each measuring cup is a suitable opening 22 in which is installed a tube 23 extending some distance within the cup and also above same. This tube is connected by means of 90 a flexible tube 24 to a second upright rigid tube 25 the upper end of which is above the discharge opening of the bottles 17 so that in no event liquid within the tubes will rise to a level above the extreme upper end of the 100 110

tube 25. The tube 23 is so positioned within the opening 22 as to permit of vertical adjustment and by which the amount of liquid in the cup 17 may be measured or predetermined, as for example when the tube 23 is lowered within the cup the latter will fill with liquid to a lesser height than when the tube is raised to a higher level in the cup. By this arrangement the amount of liquid 10 discharged at a single operation within one of the drinking cups 26 is readily predetermined.

In the embodiment here shown I have illustrated a series of 6 measuring cups, 15 coils and bottles, this being an appropriate number for such a machine though such number forms no part of the invention as is evident.

Within each cylinder 20 is installed a 20 reciprocal piston 27 and rod 28 there being an expansive spiral spring 29 intermediate of the piston and outer end of the cylinder, which normally tends to keep the piston inwardly past the opening or port 21 to the 25 drinking cup, which permits of the liquid readily flowing into the latter from its respective coil 15, the measuring cup remaining filled at all times when there is sufficient supply of liquid except when the 30 emptying process is carried on. Each cylinder 20 is provided with a discharge port or opening 30 in the lower wall thereof and which port communicates with the inwardly protruding tubular extension 31 to the end 35 of which a flexible tube 32 is attached and leads in any convenient manner to the discharge nozzle 33 mounted upon the deck 2 and near the forward edge thereof, said nozzle being so positioned as to conveniently 40 discharge into one of the drinking cups 26 when the latter is positioned thereunder for filling. Thus it is evident that when the piston 27 is in the position shown in Fig. 1 of the drawings the liquid within the measuring cup will pass through the port 21 into the cylinder 20 thence through the port 30, the extension 31, tube 32 and nozzle 33 into the drinking cup whereas when the piston is allowed to assume its normal position between the ports 21 and 30 by the action of 50 the spring 29 the measuring cup will again be filled by opening the communication through the port 21 and cylinder 20 with its respective coil 15.

55 Each piston rod 28 extends inwardly, they forming a battery of spaced rods in front of the reciprocal carriage 34 which is positioned transverse the machine and spans the flexible tubes 32. Upon the carriage is mounted a transversely reciprocal rack 35 which has an L-shaped extension 36 upon the face thereof toward the receptacle 14 and which extension is designed to engage any one of the piston rods 28 and force it 60 toward the receptacle 14 when the carriage

is similarly reciprocated thus counteracting the action of the spring 29 at the opposite end of the piston rod when thus engaged.

On top of the L-shaped extension 36 is an indicator-arm 37 which reaches upwardly 70 and over a transversely disposed name-plate 38 superimposed on the opposite side of the carriage 34 to that of the extension 36. By this arrangement the lateral position of the L-shaped extension 36 is clearly indicated 75 upon the name plate 38 which may have horizontally indicated thereupon the different kinds of beverages being dispensed in the machine. Longitudinal motion of the rack 35 is imparted by means of the spur 80 gear or pinion 39 mounted upon the manually operated shaft 40 the opposite end of which extends to a convenient position for access by the purchaser. When the carriage 34 is in its operative position as shown in 85 Fig. 1 the gear 39 is out of engagement with the rack 35 and when said rack is withdrawn ready for a subsequent operation the gear 39 again comes into meshed relation with the rack, the forward end of the gear 90 39 being somewhat pointed or tapered as at 41 for conveniently mounting the edge of the rack as the latter is drawn toward the gear, the innermost bearing 42 of the shaft 40 being mounted on a telescopic standard 95 indicated at 43 for permitting the gear 39 to raise slightly when mounting the rack 35 and possibly out of mesh therewith but which will be properly engaged when 100 slightly rotated in either direction.

A contractile spring 44 is provided about the upright or standard of the bearing 42 one end being attached to the upper portion of the bearing and the other to the lower, which will assist in keeping the pinion 39 properly in place within the rack 35. The opposite ends of the carriage 34 are each provided with an elongated slidable supporting member 45 carrying a roller 46 which intermittently become engaged within the slot 47 formed in the inner face of the disks 48 which are rigidly fixed to the transverse shaft 49 journaled upon the deck 2, and rotate with same. This shaft has fixed upon one end thereof a worm gear 50 meshing with the worm 51 on the shaft 52 which transmits power and motion to the shaft 49 from the electric motor 69 the connection with said motor not being material in this invention other than it provides the necessary motion and power for the proper functioning of the different parts of the device.

Each disk 48 is provided with a slot 47 as before described, and adjacent the outer edge of the receiving end of each slot is a 125 guiding clip 53 attached to the circumferential edge of the disk and is provided for the convenient and sure entrance of the rollers 46 into said slots.

In the circumferential edge of the disk 130

48 nearest the shaft 4 is a through Z-shaped slot 54 which is designed to receive the upper reduced ends of the posts 10 when the latter are held by the rotative action of the 5 spring 11 against the edge of said disk and this slot is arranged in such a manner as to permit of the table 3 being rotated one step while bringing a drinking cup into position under the nozzle 33 just prior to the advance 10 of the carriage 34 and prior to its opening communication with one of the measuring cups, this occurring by the upper end of one of the posts 10 passing through the Z-shaped slot 54 the latter being Z-shaped, that is having a straight central portion to prevent the 15 table 3 from running away.

Intermittent rotative action is imparted to the shaft 4 by means of the reciprocal arm 55 mounted upon a suitable cam 55' on 20 the shaft 49 and carrying the dog 71 which engages the ratchet wheel 58 securely fixed to said shaft 4 and by which it is evident that at each rotation of the shaft 49 the shaft 4 will be given one fraction of a revolution and which fraction in this case is one-sixth, to correspond with the units involved in the machine. Upon the outer face of the disk 48 nearest the shaft 4 is fixed an annular rim 56 which has a notch formed there- 25 30 in as indicated at 57 said notch being abrupt at one termination and tapering gradually to the full depth of the ring at its opposite termination.

A spring controlled reciprocal rod 58 is 35 mounted upon the deck 2 and intermittently engages the edge of the ring 56 it being held toward said ring at all times by the action of the contractile spring or other suitable means indicated at 59. A fixed pin 60 operating in the slot 61 in the outer end of 40 the rod 58 governs the throw in either direction of the rod and the extension 62 on the outer end of the rod operates back and forth in the opening or notch 63 transverse the 45 inner edge of the vertically disposed coin conveying conduit 64 which is fixed upon the deck 2 and receives the coin which controls the operation of the machine. This control is accomplished in the following 50 manner; assuming that the machinery is properly set for operation the rod 58 will be in its innermost extended position within the notch 57 and not engaging any portion of the ring 56, this bringing the extension 55 62 upon said rod within the notch 63 and in the path of the coin 65. When this position- 60 ing of the rod is accomplished the coin 65 will rest upon the extension 62 of the rod 58 which forms parts of the electric circuit that 65 operates the motor 69 the electrical connec- 125 tion with the rod 58 being shown at 66. The conduit 64 is also in the electrical circuit of the motor and said circuit is normally broken or open intermediate of the rod 58 and the conduit 64, however when a coin is

dropped into the conduit and rests upon the projection 62 some portion of the coin will engage the conduit and thus close the motor circuit. The instant this is accomplished the disks 48 will commence to rotate by the 70 action of the motor and at a suitably predetermined point in the operation of the device the inner end of the rod 58 will contact the inclined edge of the ring 56 as the latter rotates and which engagement will tend to 75 force the rod 58 outwardly and close the by-pass circuit 67 intermediate of the rod 58 and the electric motor by dropping of the coin, the ring terminal of said by-pass circuit being accomplished after the coin has 80 dropped by a spring contact 70 continuously engaging the undermost surface of said ring.

The rotative motion of the disks 48 will thus continue until such time as the rod 58 again drops into the notch 57 past its abrupt 85 termination when both circuits to the motor will be broken, thus stopping the mechanism, which will await the subsequent deposit of a coin, it being noted that when the rod 58 reaches its outermost termination the 90 extension 62 will pass from beneath the coin and allow it to pass through the conduit and become deposited as compensation for the operation of the machine.

When such cycle of the device takes place 95 the crank-arm 68 attached to the disk 48 next to the shaft 4 will properly reciprocate the handle 7 of the cup-feeding mechanism and a cup will be deposited in the table 3 just prior to its advancement which takes 100 place as previously described, all the other elements of the mechanism properly functioning in step as is obviously necessary for the successful working of the device.

The initial operation of the device in selecting the desired beverage is accomplished by first pushing inwardly the shaft 40 until the gear 39 is in mesh with the rack 35, when said shaft 40 is rotated in either direction until the indicator 37 is moved laterally to 110 the desired beverage as shown on the name plate 38 which will bring the L-shaped extension 36 opposite the proper rod 28 for dispensing such beverage. Then, as manual contact with the shaft 40 is released it will 115 assume its normal retracted longitudinal position free from engagement with the rack, when the dispensing mechanism is ready to operate by the deposit of the coin which will close the circuit to the motor as 120 previously described.

The motor now having been set in motion, the disks 48 will proceed to rotate, but a slight motion of which will bring the radial slot 54 in the disk 48, which controls the operation of the table 3, opposite the reduced upper end of the post 10 allowing the latter to pass therethrough as previously described until the succeeding post 10 strikes against the side of the disk and the table 3 stopped 130

thereby. This will bring the cup 26 in position beneath the nozzle 33 ready to be filled and there held until the next action of the table 3. Prior to such initial operation it is to be understood that the rollers 46 are within their respective slots 47 in the disks 48 in their innermost position in relation to the disks as shown in Fig. 1 of the drawings, and the pistons 27 of the rods 28 in all of the cylinders 20 are in a position intermediate of the ports 21 and 30 closing communication between said ports. Now as the disks proceed to rotate the changing position of the slots 47 will cause the rollers 46 to move outwardly to the circumferential edges thereof and when the rollers are bearing only against such portion of the disk, the piston rod 28, against which the L-shaped extension impinges, will be extended to its farthest open position permitting the liquid from its respective measuring cup to pass in to the drinking cup through the cylinder 20 and its connections. It is to be understood that the length of the slots 47 in relation to the circumference of the disks is such as to properly allow for all of the liquid in the measuring cup to be emptied and the notch 57 in the ring 56 is so positioned as to receive the rod 58 and stop the operation of the motor by opening the circuit thereto as previously described in proper time to again receive the rollers 46 in the slots 47 ready for a subsequent operation of the machine, the springs 29 back of the piston 27 operating to return the piston to its position between the ports 21 and 30 to normally maintain closed relation between said ports.

While I have shown a specific structure as embodying the invention it is to be understood that various modifications may be resorted to without departing from the spirit thereof.

Having thus described my invention, what I claim and desire to secure by Letters Patent is:

1. In combination a suitable support, a cooling receptacle, a liquid supply, a measuring cup, a drinking cup, means for automatically emptying the measuring cup into

the drinking cup, means for automatically supplying the cups to be filled, an operating motor, an electric circuit for the motor, means whereby the deposit of a coin will close the circuit and start the motor and a second means for closing the circuit and completing the operation of the machine.

2. The combination with a motor operated beverage dispensing device of the character described comprising a liquid supply, cooling means, measuring cup and drinking cup, of means whereby the deposit of a coin will start the motor and means independent of the coin for continuing the action of the motor to cause the machine to dispense one cup of the liquid which it contains.

3. The combination with a motor driven beverage dispensing device of the character described having a plurality of beverage supplies, cooling means, a measuring cup and a drinking cup, of means whereby the selection of any one of the beverages may be predetermined and means whereby the deposit of a coin will automatically start the machine and other means whereby to cause the continuation of such operation to dispense that beverage which was previously determined upon.

4. The combination with a liquid vending device of the character described having a plurality of liquid supply containers, a co-operative indicator and adjuster whereby the machine may be set to dispense any one of the different liquids to be vended, a co-operative cup container and delivery device and a discharge nozzle and a motor for automatically operating the device, of a rotatable cup delivering table beneath the cup container and nozzle means whereby the depositing of a coin will start the motor and means whereby a cup is automatically conveyed from the container to the nozzle for the reception of the liquid being vended.

In testimony whereof I hereunto affix my signature in the presence of two witnesses.

JULIUS S. SAMUELSON.
